UNITED STATES PATENT OFFICE.

JOSEPH DEPTA, OF PASSAIC, NEW JERSEY.

LIFE-PRESERVER.

1,111,010.

Specification of Letters Patent. Patented Sept. 22, 1914.

Application filed June 19, 1914. Serial No. 846,081.

To all whom it may concern:

Be it known that I, JOSEPH DEPTA, a subject of the Emperor of Austria-Hungary, residing at Passaic, in the county of Passaic 5 and State of New Jersey, have invented certain new and useful Improvements in Life-Preservers, of which the following is a specification.

This invention relates to certain new and 10 useful improvements in life preservers.

The primary object of this invention is to provide separate extremely light floating elements shiftably positionable beneath the arms of a person and there secured against 15 removal, offering no obstruction to the movements of the person, while at the same time affording buoyancy to the body.

A further object is to provide inflated floats after the manner of water wings and 20 having an arrangement of securing straps for attaching said floats to the body.

A still further object is the positioning of pneumatic floats beneath the arms of a person in such a manner that the upper portions 25 of the floats are rigidly held while the lower portions thereof are slidably shiftable upon the belt of the wearer.

With the above general objects in view and others that will appear as the nature of 30 the invention is better understood, the same consists in the novel combination and arrangement of parts hereinafter more fully described, illustrated in the accompanying drawings, and pointed out in the appended 35 claims.

In the drawings forming a part of this application and wherein like numerals of reference designate corresponding parts throughout the several views:—Figure 1 is 40 a front elevation of the device detached. Fig. 2 is an elevation view of the inner surface of one of the floats showing the connecting straps broken away, and, Fig. 3 is an enlarged elevation of the lower portion 45 of one of the floats showing the sliding belt arrangement, and the shiftable connecting strap thereon.

Referring more in detail to the drawings, 50 the floats 10, it will be noted, consist of substantially shield-shaped pneumatic cushions adapted to be inflated with air forced through the nipple arrangement 11 of each float while the upper portion of the float is cut-away forming an arm-receiving socket 55 12.

The floats 10 being arranged in pairs, it

is to be noted that the same are positionable at the opposite sides of the wearer and beneath the arms and with the sockets 12 of the floats positioned at the arm pits of the wearer while shoulder straps 13 carried by each float adjacent the arm socket 12 thereof are buckled around the arms of the wearer at the shoulder for supporting the floats in their proper positions. A chest 60 strap or belt 14 is secured between the two floats 10 and adapted to encompass the upper portion of the wearer's body at a point above the chest and be tightened and retained in position by means of the buckle 15 and whereby the floats are securely strapped 65 with their upper portions fixed to the body of the wearer. A waist strap or belt 16 is threaded through loops 17 carried on the inner faces 18 of each of the floats and is 70 adapted to encircle the waist of the wearer and secured by means of the buckle 19 and by which arrangement it will be seen that the lower portions of the floats may be 75 slightly shifted upon the belt when secured to the wearer. A retaining strap 20 has its opposite ends provided with loops 21 which are slidably-mounted upon the waist belt 16, the said retaining strap being adapted to 80 be positioned between the legs of the wearer and secured by means of the buckle 22, and whereby as will be evident, the waist strap 85 as well as the floats are prevented from rising unduly or moving upwardly when the wearer is in the water partially supported 90 by the floats. The present device is thus readily secured upon the body and is employed both as a life preserver as well as a means to aid a person in swimming and is 95 designed both for the preventing of accidents, as well as used for pleasure.

While the forms of the invention herein shown and described are what are believed to be preferable embodiments thereof, it is nevertheless to be understood that various 100 forms, modifications, and arrangement of the parts may be had without departing from the spirit and scope of the invention as claimed.

What I claim as new is:—

1. A device of the class described, comprising two pneumatic floats provided with arm sockets at the tops thereof adapted for positioning beneath the arms of the wearer, retaining straps secured to said floats adjacent said sockets and adapted to be secured around the wearer's arms, a chest-encircling 105
- 110

2
strap secured between said floats, loops secured to the opposite inner flat surfaces of said floats, a waist belt slidably-positioned through said loops and adapted for encircling the wearer's waist, and a retaining strap slidably connecting the front and rear portions of said waist belt and adapted to be secured between the legs of the wearer.

2. A device of the class described, comprising shield-shaped pneumatic floats having top cut-away portions, arm-encircling straps connecting the opposite sides of said cut-away portions, a chest-encircling strap rigidly-secured between the upper portions

of said floats, a waist belt strap slidably attached to the lower portions of said floats at opposite points upon their inner faces, and a retaining strap slidably-secured to said waist belt adapted to restrain said floats against upward movement upon the wearer's body. 15
20

In testimony whereof I affix my signature in presence of two witnesses.

JOSEPH DEPTA.
